RECIPROCATING PUMP

Elliott F. Wright, Summit, and Arthur G. Rockwood, Nutley, N. J., assignors to Worthington Corporation, a corporation of Delaware

Application November 22, 1946, Serial No. 711,546

1 Claim. (Cl. 103—153)

1

This invention relates to reciprocating pumps and particularly to such pumps for pumping fluids containing a percentage of solids, such as sewage or the like.

In pumping sewage particularly as well as in some other pumping installations, the pumps inevitably become clogged with foreign matter which must be removed to permit proper operation of the pump, and it is an object of the present invention to provide a pump for such service which can be quickly and easily cleaned, and any clogging foreign matter removed from the valve of the pump without requiring dismantling of the pump.

Another object of the present invention is to provide a reciprocating pump for such services as specified which provides a straight pump-through flow of liquid pumped, as well as one in which a novel type and arrangement of valves is employed resulting in simplified construction, elimination of angles and curves in the flow path of fluid pumped, as well as a pump structure from which the valves may be easily removed.

A further object of the present invention is to provide a pump of relatively small capacity to operate under a low discharge head which will have passages and valves of sufficient area to pass a certain amount of solids.

With these and other objects in view, as may appear from the accompanying specification, the invention consists of various features of construction and combination of parts, which will be first described in connection with the accompanying drawings, showing a reciprocating pump of a preferred form embodying the invention, and the features forming the invention will be specifically pointed out in the claim.

In the drawings:

Figure 1 is a side elevation of the pump. Figure 2 is an end elevation of the pump.

Figure 3 is a vertical section through the pump taken on the line 3-3 of Figure 4.

Figure 4 is a vertical section through the pump taken on the line 4—4 of Figure 3.

Figure 5 is a horizontal section through the pump taken on the line 5-5 of Figure 4.

Referring more particularly to the drawings the improved reciprocating pump includes a

The improved reciprocating pump includes a housing 1 having a pulsation chamber 2 therein into which the inlet passage 3 of the pump opens in straightaway alignment with the outlet or discharge passage 4 of the casing.

The fluid or liquid to be pumped is drawn into and discharged from the pulsation chamber 2 by means of a piston 5 which reciprocates in the cylinder 6 disposed at right angles to the axis of

the inlet passage 3 and discharge passage 4. The cylinder 6 opens into the pulsation chamber 2 so that when the piston 5 moves upwardly on its suction stroke liquid will be drawn into the pulsation chamber past the inlet valve 7, which will be drawn open by the suction stroke of the piston 5. During the downward or discharge stroke of the piston 5 the inlet or suction valve 7 will be forced against its seat and the pressure created by the downward stroke of the piston will unseat the discharge valve 8 and force the liquid from the pulsation chamber 2 out through the discharge 4.

15 The piston 5 has a double cup packing 9 carried thereby and held in place by the removable head 10 of the piston, which double cup packing will permit the pump to operate with a suction lift without air leakage.

20 A connecting rod 11 is connected to the piston 5 and is also eccentrically connected to a disc 12 mounted on the shaft 13 of a geared head motor 14 of any approved type. The disc 12 and its manner of connection with the connecting rod 25 form a crank for reciprocating the piston 5 by rotation of the motor shaft 13.

The inlet valve 7 and the discharge valve 8 are alike in construction, each comprising a substantially semi-spherical head 16 which seats against a valve seat 17. The head 16 of each valve structure is detachably connected by a suitable cap screw 18 to a flat resilient strip 19. The strips 19 may be of rubber or similar material or may be flat springs of metal as desired.

The strips 19 are bent substantially at right angles and have their ends remote from the valve heads 16 detachably connected by cap screws 20 to removable cover plates 21 and 22. The cover plate 21 which carries the inlet valve structure 7 closes an opening which opens into the pulsation chamber 2, while the cover plate 22 which carries the discharge valve structure 8 opens into the discharge passage 4 of the pump. The cover plates 21 and 22 are attached to the housing 1 by wing nuts 23 so that they may be easily removed for removing the valve structures 7 and 8 from within the housing to permit cleaning of the valves and the removal therefrom of foreign matter which might get wound around them during operation of the pump. When the cover plates 21 and 22 together with the valve structure carried thereby are removed any foreign matter in the pulsation chamber 2 may be easily removed or allowed to drain through the openings 24 into a suitable catch pan or basin as shown at 25 in dotted lines in Figure 3 of the drawings.

The resilient strips 19 have sufficient resiliency

to permit the valves 7 and 8 to be moved on or off their seats by operation of the piston 5 to provide for proper operation of the pump.

If it is so desired eye-bolts as shown at 26 may be connected to the covers 21 and 22 to facilitate their handling during disconnection from or connection to the housing 1.

Suitable gaskets are employed at all leakage joints of the pump as is usual in pump construction.

As will be seen from the drawings taken in connection with the foregoing description a pump has been provided for low capacity relatively low discharge head operation, which is capable of passing a relatively large amount of solid matter contained in the fluid pumped and that a minimum of angular bends or surfaces are provided in the flow passage of the fluid, which would interfere with the passage of solids through the pump, and that any solids or stringy foreign matter which might accumulate in the pump or upon its valves may be removed with a minimum of effort and expense.

It will be understood that the invention is not to be limited to the specific construction or arrangement of parts shown, but that they may be widely modified within the invention defined by the claim.

What is claimed is:

In a reciprocating pump for a sewage system, a housing having a pulsation chamber therein parallel to the horizontal axis thereof, a cylinder in said housing communicating with the upper end of said pulsation chamber, a reciprocating pumping piston in said cylinder, and means for reciprocating said piston, said pulsation chamber provided with a horizontally disposed inlet passage having its longitudinal axis in axial alignment with said pulsation chamber and disposed at all points thereof above the lower portion of said pulsation chamber to form a trap in said chamber for semi-solids, said pulsation chamber provided with a discharge passage op-

posite said inlet passage having its longitudinal axis parallel to and above the longitudinal axis of said inlet passage at all points therealong, an inlet valve in said pulsation chamber to open and close said inlet passage responsive to movement of said pumping piston to control the flow of sewage from said inlet passage to said pulsation chamber, a discharge valve in said discharge passage to open and close said discharge passage responsive to movement of said pumping piston to control the flow of sewage from said pulsation chamber to said discharge passage, said housing provided with a first opening into said pulsation chamber and a second opening into said discharge passage, a first and a second removable closure plate to cover said openings in the housing, said inlet valve being attached to, wholly supported by and removable in assembled condition with said closure plate for the pulsation chamber, and said discharge valve attached to, wholly supported by and removable with the closure plate for said discharge passage.

ELLIOTT F. WRIGHT.
